UNITED STATES PATENT OFFICE

WILLIAM S. TOWNSEND, OF NEW BRIGHTON, PENNSYLVANIA, ASSIGNOR TO PENNSYLVANIA NOVELTY COMPANY

DESIGN FOR A GAME TABLE

Application filed December 28, 1931. Serial No. 42,266. Term of patent 3½ years.

To all whom it may concern:

Be it known that WILLIAM S. TOWNSEND, a citizen of the United States, residing at New Brighton, in the county of Beaver and State of Pennsylvania, has invented a new, original, and ornamental Design for a Game Table, of which the following is a specification, reference being had to the accompanying drawings, forming a part hereof in which

I claim:

The ornamental design for a game table as shown.

In testimony whereof I affix my signature.

WILLIAM S. TOWNSEND.
